UNITED STATES PATENT OFFICE

2,599,818

APPARATUS FOR DRIVING WEDGES IN
ARMATURE SLOTS

William L. Evans, Gary, Ind.

Application May 9, 1946, Serial No. 668,345

3 Claims. (Cl. 29—203)

1

This invention relates to apparatus for driving out wedges and more particularly for driving out retainer wedges which are used to secure armature windings in place. Armature windings are received in slots in the armature body which is made by assembling together a large number of relatively thin circular metal discs. Each disc is provided with circumferentially spaced openings of a shape and size to receive the armature windings, the insulating medium, and the wedge which rests on top thereof. The discs are die-punched so that sharp or slightly burred edges exist around the edges of the slot. Furthermore, there may be slight misalignment of the discs during assembly into the armature body. As a result, the slot formed is generally slightly irregular in contour and presents sharp or burred edges which obstruct the movement of the wedge therethrough. Prior to my invention, great difficulty was encountered in driving the wedges in and out of the slots. This was commonly done by inserting a flat steel bar into the slot and pounding on it with a mallet. The bar often bent and caught on the edges of the discs in the slot. The wedge itself was damaged and even completely destroyed at times.

It is an object of my invention to provide a tool which is simple in construction and positive in action for use in driving wedges into and out of armature slots.

This and other objects will be more apparent after referring to the following specification and attached drawings, in which:

Figure 1 is a side view of the tool;

Figure 2 is a sectional view taken on the line II—II of Figure 1;

Figure 3 is a sectional view taken on the line III—III of Figure 1; and

Figure 4 is an end view of the tool showing it in operating position on a wedge.

Referring more particularly to the drawings the reference numeral 2 indicates the body of the tool which is made from two elongated clamping members 4 and 6 fastened together by means of two bolts 8, each of which passes through a countersunk opening 10 in member 4 and an opening 12 in member 6 with the countersunk head of the bolt being flush with the outside of member 4. The member 6 is provided with a recess 14 at its lower longitudinal edge adjacent the member 4. The recess 14 extends substantially throughout the length of the body but terminates a short distance from the rear end thereof to provide a shoulder 16. A driving member 18 is received in the recess 14 and extends therefrom with its exposed lower longitudinal

2

edge being provided with serrations 20 as best shown in Figure 1. The end of the driving member 18 bears against the shoulder 16. By drawing the members 4 and 6 tightly together by means of the bolts 8, the driving member 18 is clamped securely in place with rearward movement thereof being prevented by the shoulder 16. Protruding plates 22 and 24 are welded to the outside of plates 4 and 6, respectively. The plates 22 and 24 each have a semi-circular bearing surface 26 merging with an inclined rearwardly extending portion 28 which forms an angle of less than 45° with the longitudinal axis of the body 2. The plates 4 and 6 have a cut-out portion 30 at their upper edge which coincides with the sloping portions 28. The fork 32 of a spindle 34 passes over the body member 2 and is pivotally secured thereto by means of a pin 36 which passes through aligned openings in the fork 32 and clamping members 4 and 6. The free end 38 of the spindle 34 is shaped so as to be received in an air gun 40.

As shown in Figure 4, the armature body 42 which is made up of a great number of relatively thin circular metal discs is provided with circumferentially spaced openings 44. Each of the openings 44 has a substantially square cross-sectional portion with the upper part thereof merging into a pair of wedge surfaces 46 which extend to within a short distance of the outside of the armature body 42. A narrow slot 48 extends from the outer portion of the wedge surface 46 to the outside of the body. Each opening 44 has windings 50 therein surrounded by insulation 52. A wedge 54 bearing against the wedge surfaces 46 hold the windings 50 and insulation 52 in place. The wedge 54 is ordinarily made of wood, fibre, Bakelite, Micarta, or like material.

40 The method of driving out the wedge is as follows:

The air gun 40 is placed on the free end 38 of the spindle 34 and the serrated edge 20 of the tool is placed on a wedge 54. The spindle 45 and air gun are positioned substantially as shown in dotted lines in Figure 1 and air is momentarily applied to the air gun 40 to force the serrated edge 20 of the tool into the wedge 54 a slight distance in order to prevent slipping of the tool on the wedge as it is driven out. The spindle 50 34 and air gun 40 are then lowered rearwardly until the fork 32 rests on the surfaces 28. Pressure is then applied to the tool tending to move it to the right as shown in Figure 1 and at the 55 same time air is admitted to the air gun 40.

The staccato like blows of the gun 40 create

a multitude of vibrations in the wedge 54 which combine with the force of the forward pressure to cause the wedge 54 to be driven out of the armature slot. The multitude of vibrations created in the wedge prevent it from sticking to the sides of the slot and allow it to be freely removed. The wedges 54 can also be driven into place in the same manner.

While one embodiment of my invention has been shown and described it will be apparent that other adaptations and modifications may be made without departing from the scope of the following claims:

I claim:

1. A wedge driving tool comprising an elongated body member, a driving member fastened to one longitudinal edge of the body member and extending therefrom, serrations on the exposed longitudinal edge of the driving member, a spindle pivotally mounted on said body member at a point substantially midway of the length thereof, an air gun, a portion on the end of said spindle received in said air gun, said spindle being movable from a position substantially perpendicular to the longitudinal axis of the body member to a rearwardly extending position making an angle of less than 45° with the longitudinal axis of the body member, and stop means on said body member for preventing movement of said spindle beyond said positions.

2. A wedge driving tool comprising a pair of elongated clamping members, one of said members having a recess formed in the longitudinal surface adjacent the other member, a driving member in said recess, said driving member extending from said recess and having serrations on its exposed longitudinal edge, means for clamping the pair of members together to lock the driving member in place, a spindle pivotally mounted on said driving members at a point substantially midway of the length thereof, an air gun, a portion on the end of said spindle received in said air gun, said spindle being movable from a position substantially perpendicular to the longitudinal axis of the clamping members to a rearwardly extending position making an angle of less than 45° with the longitudinal axis

of the clamping members, and stop means on said body member for preventing movement of said spindle beyond said positions.

3. A wedge driving tool comprising a pair of elongated clamping members, one of said members having a recess formed in the longitudinal surface adjacent the other member, said recess having a shoulder at one end thereof, a driving member in said recess bearing against said shoulder, said driving member extending from said recess and having serrations on its exposed longitudinal edge, means for clamping the pair of clamping members together to lock the driving member in place, a spindle pivotally mounted on said driving members at a point substantially midway of the length thereof, an air gun, a portion on the end of said spindle received in said air gun, said spindle being movable from a position substantially perpendicular to the longitudinal axis of the clamping members to a rearwardly extending position making an angle of less than 45° with the longitudinal axis of the clamping members and stop means on said body member for preventing movement of said spindle beyond said positions.

WILLIAM L. EVANS.
